(57) **CLAIM**

The ornamental design for a bench, as shown and described.

DESCRIPTION

FIG. 1 is an isometric view of a first embodiment of the bench of the present design;

FIG. 2 is a front elevation view thereof, the rear elevation view being identical thereto;

FIG. 3 is a top plan view thereof; and,

FIG. 4 is a right side elevation view thereof; the left side elevation view being identical thereto.

The broken line depiction is for illustrative purposes only and forms no part of the claimed invention.
